UNITED STATES PATENT OFFICE.

ANTHONY SCHNEIDER, OF WHIPPANY, NEW JERSEY, ASSIGNOR TO AMERICAN CIGAR COMPANY, OF NEW YORK, N. Y., A CORPORATION OF NEW JERSEY.

REMOVABLE CLOSURE FOR CONTAINERS.

1,403,572.

Specification of Letters Patent. Patented Jan. 17, 1922.

Application filed November 8, 1921. Serial No. 513,746.

To all whom it may concern:

Be it known that I, ANTHONY SCHNEIDER, a citizen of the United States, and resident of Whippany, in the county of Morris and 5 State of New Jersey, have invented certain new and useful Improvements in Removable Closures for Containers, of which the following is a specification.

This invention relates to closures for containers and more particularly to the type of closure which includes an inset friction cover; and has special reference to the provision of a closure of this nature constituting an improvement on the "Removable closure for containers" shown in my co-pending application, Serial No. 346,928, of December 23, 1919, the present application being a continuation in part of the said co-pending application.

20 In my said co-pending application, Serial No. 346,928, I disclose a closure construction of the dished or inset friction type in which an integral portion of the cover flange or side walls is extended inwardly to 25 form a lip adapted to be engaged for removing the closure by exerting an upward pull thereon, the exemplification shown in said co-pending application including the provision of a marginal bead located at the 30 upper edge of the cover flange or side wall with part of said bead inset or rolled inwardly to provide the engaging lip.

Although this latter construction suitably performs its intended function, I have found 35 in manufacturing the containers and closures on a very extensive scale that there are certain disadvantages incident to the insetting or inrolling step of the marginal bead in such construction, and that the closure structure may be more cheaply obtained in quantity production by producing 40 the lip in a different manner, as will be apparent in the further description of the present invention. In the operation of insetting or rolling inwardly of the bead as 45 shown in my co-pending case, besides requiring special forming implements and a relatively difficult operating step, the bead in being bent or turned and varied in length 50 during the insetting step is oftentimes marred, this requiring the necessity for selection and discarding of the misformed closures on the part of the operator, with a resulting increment added to the cost of production.

55 As a result of experiments performed

during extensive manufacture of these closures, I have found that in lieu of inturning the bead to provide the lip, that the lip may be obtained in an efficient and simple manner by merely flattening or mashing a portion thereof with the flattening or mashing effected preferably to provide a fully inset lip. The flattening or mashing is effected in a simple operation, it having been found that with the lips so formed the closures may 60 be manufactured at a reduced cost not only, but that a stronger multi-walled lip is obtained, subject to less deformation when the closure is removed forcibly from the container in which it is tightly frictionally received. The provision of an improved closure element with the lip so provided comprehends the prime desideratum of my present invention.

Other objects of my invention will be apparent from the following description taken in conjunction with the accompanying drawings, in which—

Figure 1 is a perspective view of the container with my improved closure element applied thereto and showing the manner of removing the said closure element, and

Figure 2 is a fragmentary cross-sectional view in detail taken on the line 2—2, Figure 1.

Referring to the drawings, the closure of my invention is intended for use with a container such as 10 provided with preferably straight side walls terminating at the upper end preferably in an outwardly rolled bead 90 11. While I disclose my closure as applied to a container having a smooth side wall free from inward projections, it will be apparent that any type of container having an opening for an inset friction cover may be 95 employed.

The cover of my present invention comprises the dished or inset closure generally designated as 12, having a preferably flat bottom 13 and a side wall or flange portion 100 14 which is adapted to be frictionally received by the side walls of the closure 10 to form a tight fit therewith, the cover flange or side wall 14 terminating at the upper edge in the marginal outwardly rolled bead 15. 105 The cover bead 15 is adapted to contact with the upper edge of the container walls and more specifically in the present construction, with the container marginal bead 11, the bead 11 forming a seat for the closure, the 110

bead 11 and the cooperating marginal bead 15 limiting the motion of the cover into the container.

For the purpose of providing means adapted to be engaged by the finger for moving the cover out of the container or removing the cover therefrom, a portion of the bead 15 is flattened or mashed to provide the lip portion 16. The flattening or mashing of the bead is effected so as to preferably provide a completely inset lip 16, as clearly shown in the drawings. When so constructed or formed, a multi-walled lip is effected which has been found strong and effective for the purpose intended, the lip resisting deformation when the fingers are inserted therebeneath and when the cover is removed from the frictionally retaining container walls, it having been further found, as heretofore referred to, that the cost of production of the closure is lessened by the flattening or mashing of the bead in the manner described.

The manner of making and the manner of using my improved closure will be fully apparent from the above detailed description thereof. It will be further apparent that I have provided an improved closure which may be produced cheaply and effectively in quantity production, providing a closure having, moreover, a uniformly neat and attractive appearance which may be easily manipulated in use.

While I have described the preferred form and use of my invention, it will be apparent that changes in form and use may be made without departing from the spirit of the invention, defined in the following claims.

I claim:

1. In combination with a container having an open end, of a dished closure having a wall adapted to be placed in and frictionally engage said open end, the dished closure be-

ing provided with a marginal bead at the upper edge of the side wall thereof, an integral portion of the said bead being flattened or mashed to provide an inwardly formed lip adapted to be engaged for removal of the closure by an upward pull thereon. 45

2. In combination with a container having an open end, of a dished closure having a wall adapted to be placed in and frictionally engage said open end, the dished closure being provided with an outwardly turned bead along the upper edge thereof adapted to seat over the open end of the container to limit the motion of the closure into the container, an integral portion of the said bead being flattened or mashed to provide an inwardly formed lip adapted to be engaged for removal of the closure by an upward pull thereon. 50

3. In combination with a container having vertical straight side walls free from inward projections and open at an end and a dished cover for closing the container, said cover including a relatively flat bottom portion, a side wall substantially at right angles thereto and adapted to frictionally engage the side walls of the container, an outwardly extending bead along the upper edge of the side wall adapted to engage the upper edge of the container to limit the motion of the cover into the container and means for facilitating the removal of the cover, said means including a portion of said bead flattened or mashed and inwardly set, providing an inwardly directed multi-walled lip spaced from the bottom portion of the cover and adapted to be 60 grasped by the fingers to exert an upward pull thereon for removal of the cover. 75

Signed at New York City, in the county of New York and State of New York, this 7th day of Nov., A. D., 1921.

ANTHONY SCHNEIDER.
